DRAFT GEAR

Ernest H. Schmidt, Cleveland Heights, Ohio, assignor to National Malleable and Steel Castings Company, Cleveland, Ohio, a corporation of Ohio

Application December 31, 1930, Serial No. 505,793

5 Claims. (Cl. 213—22)

This invention relates to railway draft gears. A feature of the invention is the provision of a novel and improved draft mechanism not only effective in draft or pull but furthermore providing a greater shock absorbing capacity in buff than in draft, whereby increased capacity is rendered available for the absorption of the comparatively heavy shocks which occur in buff. In carrying out the invention I provide shock absorbing means having a greater effective travel in buff than in draft. A further feature of the invention comprises the provision of a draft mechanism comprising a member mounted for movement in buff but not in pull and engaged by means for generating friction in cooperation with said member for absorbing shocks; relative movement between said member and a portion of said friction generating means being provided in draft, and between said member and the entire friction generating means in buff. Other features of the invention will be hereinafter described and claimed.

In the accompanying drawings:

Fig. 1 is a view, in side elevation, with certain parts in vertical section, illustrating an embodiment of my invention.

Fig. 2 is a horizontal sectional view, partly in plan, on line II—II of Fig. 1.

Fig. 3 is a transverse vertical sectional view on an enlarged scale, taken on line III—III of Fig. 1.

Fig. 4 is a transverse vertical sectional view on line IV—IV of Fig. 5.

Fig. 5 is a longitudinal vertical sectional view on an enlarged scale, of the draft gear shown in Figs. 1 and 2.

Fig. 6 is a horizontal sectional view on line VI—VI of Fig. 5.

Fig. 7 is a detail view, partly in vertical section and partly in elevation illustrating the manner in which the retaining bolts may be applied to and removed from the gear case.

Fig. 8 is a transverse vertical sectional view on line VIII—VIII of Fig. 7, with the retaining bolt omitted.

Figs. 9 and 10 are detail perspective views of a washer which cooperates with the retaining bolt.

Fig. 11 is a view partly in side elevation and partly in vertical section of a modified form of draft gear embodying my invention.

Fig. 12 is a transverse sectional view on line XII—XII of Fig. 11.

Fig. 13 is a view partly in plan and partly in horizontal section on line XIII—XIII of Fig. 11.

Referring to Figs. 1 and 2 of the drawings, a

standard coupler shank is shown at 5, and is connected to a horizontal yoke 6 by a key 7 extending horizontally through a slot in said shank and through slots 8—8 in the arms of said yoke. Between the butt of the coupler shank and the rear wall 6' of said yoke there is interposed a draft gear comprising a case 9 and a pair of followers or wedge members 10, 11 extending into the ends of said case. At the rear of the yoke and secured to the draft sills 12—12 is a conventional stop element 13. Carrier irons 14, 15 are secured to the draft sills and serve to support the draft gear. The usual cover plate is shown at 16. The key 7 extends through slots 12'—12' in the draft sills as indicated.

The draft gear case 9, as shown in Figs. 3—6, may be rectangular in form and is shown provided with an integral web 17 extending horizontally across the interior of the case in the central portion thereof. A recess 18 extends through said web and through the side walls of the case; and there is passed through said recess a key 19 which extends through slots 20—20 in the arms of the yoke 6 and thence through slots 21—21 in the draft sills. Vertical walls or partitions 22, 22 extend across the case 9 above and below the web 17, and, as shown, merge into said web, one of said partitions 22 also merging with the top wall 23 of the case and with the side walls 24, 24, and the other of said partitions merging with said side walls and with the bottom wall 25 of the case.

Through the walls or partitions 22, 22, the case 9 is divided into forward and rear compartments 26, 27 respectively, in each of which compartments there is positioned shock absorbing mechanism cooperating with the corresponding wedge members 10, 11. The shock absorbing mechanisms in said compartments are shown as duplicates of each other, although, if desired, different forms of shock absorbing mechanisms may be employed in the respective compartments.

Each of the shock absorbing mechanisms herein shown in the compartments 26, 27 comprises a pair of friction members 28, 28, seated in opposite side walls 24, 24 of the case 9. Said friction members are shown in the form of rectangular blocks having lateral projections 29 at their inner ends, each of said projections entering a corresponding one of a plurality of recesses 30 in the side walls of the case. To resist the inward thrust of the friction members 28 the case 9 is provided with abutments 31 against which the members 28 bear at their inner ends.

On opposite sides of each of the friction members 28 and in frictional engagement therewith

are arranged friction shoes 32; there being two friction members and four shoes in each compartment 26, 27. Each shoe comprises a projection 32' extending inwardly along the associated friction member and also comprises a projection 32'' having an inclined face. The inclined faces of the shoes 32 in the front compartment 26 are engaged by correspondingly inclined faces 33 of the wedge member 10, and similarly the inclined faces of the shoes 32 in the rear compartment 27 are engaged by the correspondingly inclined faces 34 of wedge member 11.

Mounted centrally within each compartment 26, 27 is a spring 35; each of said springs bearing at one end against a central portion 36 of the corresponding wedge 10 or 11 and at its opposite end against a corresponding washer element 37. The washer elements 37 are each mounted upon a respective one of a pair of bosses 38 projecting from and integral with opposite sides of the web 17. The inner sides of the abutments 31 adjacent each boss 38 are curved, as indicated at 39 in Figs. 4 and 8 to accommodate the associated spring 35.

Surrounding the central spring 35 in each compartment is a group of four springs 40, one for each of the friction shoes 32 in the compartment, and positioned in the four corners of said compartment as shown in Figs. 3, 4, and 5. Each of said springs bears at its inner end against one or the other of the central vertical walls or partitions 22, 22. At their outer ends, two of the four springs 40 in each compartment engage one of a pair of followers 41, 41 in the compartment and the other two of said springs engage the other of said followers. Each of said followers engages the inner faces 42 of the projections 32'' of a pair of the shoes 32; each follower extending from a shoe cooperating with one friction member 28 to a shoe cooperating with a friction member on the opposite side of the case 9. Each spring 40 is shown as comprising both an inner coil and an outer coil, and each follower is provided with bosses 43 extending into the inner coils of the associated springs 40 as shown in Fig. 6.

The abutments 31 are provided with upper and lower extensions 44 (Fig. 8) which merge into the walls of the case, and these extensions are provided with curved faces 45 for accommodating the springs 40, as shown in Figs. 4 and 8.

The wedges 10, 11 are maintained in assembled relation to the case 9 by bolts 46, 46. Each of said bolts at its inner end is engaged with one of the bosses 38 and at its outer end extends through the end wall 47 of a recessed portion or pocket 48 in the wedge 10 or 11. Nuts 50 are threaded on the outer ends of said bolts within said pockets. To provide for the expeditious application and removal of the bolts with respect to the case 9, I have provided the construction which will now be specifically described in connection with one of said bolts (with particular reference to Figs. 5-10).

The web 17 is provided with upper and lower slots 51 of sufficient width to permit the head of the bolt to be received therein. The boss 38 comprises an enlarged portion 38' having a recessed interior 52 shaped to receive the head of the bolt, and said boss also comprises a reduced portion 38'' recessed on its interior for receiving the body of the bolt. The bottoms of both the boss portions 38', 38'' are slotted at 53', 53'', respectively, these slots being of sufficient width to permit the body, but not the head, of the bolt to be passed therethrough. The washer 37 com-

prises a boss 54 which is adapted to extend inside the spring 35 and with an opening or recess 55 through which the body of the bolt 46 is adapted to extend. An extension 56 within said recess has its upper surface curved to form a seat for said body. Said extension also fits into the slot 53' of the boss portion 38' when the washer is in assembled relation to the boss 38. The washer 37 further comprises a projection 57 which is adapted to fit into the slot 53' in portion 38' of boss 38. Said projection 57 has its upper surface 57' shaped to conform to the head of the bolt. The washer 37 is held in position on the boss 38 by the engagement of the spring 35 with said washer.

The manner in which a retaining bolt 46 may be removed will now be apparent and is illustrated in Fig. 7, wherein said bolt is shown moved inwardly sufficiently to bring its head opposite the slots 51 in web 17. The nut 50 has, of course, been first removed from said bolt, and the associated wedge, friction shoes, and springs have been taken out of the case. The washer 37 has been slid outwardly (i. e., toward the adjacent open end of the case) so that its extensions 56, 57 are disengaged from the boss 38. It will be apparent that the bolt may now be readily moved downwardly so that its head passes through the lower slot 51 and its body passes through the slots 53', 53'' in boss 38, whereby said bolt may be removed from the case 9. Application of the bolt to the case 30 is the converse of the procedure above outlined; said bolt being first moved inwardly to bring its head below the lower slot 51 and its body below the slots 53', 53'', after which said bolt is moved upwardly and then outwardly so that its head 35 is received in the recess 52 of boss 38. The washer 37 may now be slid over the bolt to bring the extensions 56, 57 of said washer into the respective slots 53'', 53', after which the springs and associated parts may be inserted into the case.

The key 19 normally bears against the front side of the slots 21, 21 in the draft sills, as shown in Figs. 1 and 2. In draft or pull, the coupler shank 5, through key 7 and yoke 6, forces the wedge 11 forwardly. Since the key 19 engages the front sides of the slots 21, 21, the case 9 is held against forward movement, and thus the parts in the rear compartment 27 are placed under compression while those in the front compartment are not. The slots 20 in the arms of 50 the yoke 6 are of sufficient length to permit movement of the yoke and coupler shank in draft without interference by the key 19. The movement of the coupler shank in draft is transmitted to the rear wedge 11 and is resisted by the central 55 spring 35 which acts directly against said wedge, by the springs 40, which cooperate with the friction shoes 32 engaged with said wedge, and by the friction generated between said shoes and the associated friction members 28. Said shoes, 60 under the influence of the inclined surfaces 34 of said wedge 11 and the action of the associated springs 40, are maintained in firm frictional engagement with the friction members during the compression of the gear. The amount of friction developed between the shoes 32 and associated friction members 28 is dependent upon the angle of inclination of the sides of the friction members to the longitudinal axis of the gear. The faces of said friction members are 70 shown in Fig. 5, as inclined with respect to said longitudinal axis, although they may, if desired, be parallel thereto.

When the coupler shank moves in buff the yoke 6 and rear wedge 11 are prevented from rear- 75

ward movement by the stop 13, and the butt of said shank acts upon the forward wedge 10. The slots 8 in the yoke arms are of sufficient length to permit the coupler shank to move in buff without interference from the engagement of the key 7 with said arms. When the coupler shank moves in buff, said shank transmits the buffing force to the wedge 10 and the latter thereupon acts upon the friction shoes 32 and springs 35 and 40 in the front compartment 26. At the same time, the slots 21, 21 are of such length as to permit movement of the key 19 and case 9 rearwardly from their normal position shown in Figs. 1 and 2. Thus, when the coupler moves in buff the case 9 is moved rearwardly and the shock absorbing mechanism in both compartments 26 and 27 are brought into action. The slots 21, 21 may, for example, be of such length as to permit movement of the case 9 through two inches, and if the wedge 10 and cooperating friction shoes are permitted to travel two inches with respect to the case it will be seen that a total of four inches travel of the gear in buff is provided. The movement of the wedge 11 with respect to the case 9 in draft or pull may, at the same time, be two inches, with the result that the total effective movement of the gear in buff is twice the movement of said gear in pull. The extents of movement above indicated are illustrative merely and may be varied so that the movement in buff may exceed that in pull by such amount as may be desired. Buffing shocks are generally more powerful than those occurring in draft, and it will be seen that by the mechanism above described I have provided for greater shock absorbing action of the gear in buff than in pull, whereby increased capacity is available for handling the buffing stresses.

The extent of relative movement between each wedge and the case 9 is such that just before the springs go solid the peripheral flange 58 of the wedge will engage the adjacent end of said case.

While I have shown the projections 29 of the friction members 28 in firm engagement with the openings 30, a limited amount of clearance may be provided between said openings and projections longitudinally of the case. In this way the initial compression of the gear may be opposed simply by spring action and the further compression thereof by both spring action and the frictional resistance between shoes and friction members. The extent of preliminary spring action may be varied by varying the amount of said clearance and the capacity of the springs.

In the form of my invention shown in Figs. 11, 12, and 13, I have shown a friction member 60 which is engaged at one end by a pair of shoes 61, acted upon by a wedge member 62, and at its opposite end by a pair of shoes 63 which are acted upon by wedge member 64. The assembly of wedge members and friction member is interposed between the butt of the coupler shank and the rear wall 6' of the yoke 6 (Figs. 1 and 2), just as is the assembly of wedges 10, 11, and case 9; the wedge 62 being engaged by the coupler shank butt and the wedge 64 by the rear wall of the yoke when the assembly is in normal position. The friction member is provided with a slot 65 through which the key 19 may be passed.

The shoes 61 are engaged by a spring seat 66 and the shoes 63 by a spring seat 67. The friction member 60 has formed integrally therewith at its central portion a pair of upwardly extending projections 68 and a pair of downwardly ex-

tending projections 69. A web or partition 70 extends across the space between the projections 68 and is formed integrally with the friction member and with said projections. Similarly, a web or partition 71, integral with the friction member and projections 69, extends across the space between the last-mentioned projections. Interposed between the spring seat 66 and the respective partitions 70, 71, are the springs 72, 73; and likewise, springs 74, 75 are positioned between the spring seat 67 and said partitions. The inner walls of the projections 68, 69 are curved as indicated at 76 in Figure 12 to conform to the contour of the springs and to accommodate and center the latter. The spring seats 66, 67 each have side flanges 77 embracing portions of the associated springs and preventing the latter from moving out of centralized position. As shown in Figure 12, the friction member 60 comprises upper and lower surfaces of grooved formation; said friction member having on its upper surface walls 78, 79 inclined downwardly and inwardly or in other words, converging downwardly toward each other; and the lower surface of said member comprising walls 80, 81, which converge upwardly toward each other. Each of the spring seats 66, 67 surrounds the friction member 60 and may be provided with guide projections 82 extending inwardly into the grooved portions of the friction member, as indicated in Figure 11. 30

For retaining the wedge 62 in assembled relation to the friction member 60, bolts 83, 84, are provided; the bolt 83 passing through projection 69 of the friction member and through a lug 85 on the wedge 62, and the bolt 84 passing through projection 68 and through a lug (not shown) on the wedge similar to lug 85 but diagonally opposite the same as will be apparent from Figures 11 and 12. Similarly the wedge 64 is maintained in assembled relation to the friction member by bolts 86, 87 diagonally opposite each other; each of said bolts passing through a respective one of the projections 68, 69 and through a corresponding one of diagonally opposed ears on wedge 64, one of said ears being indicated at 88. The heads of the bolts 83, 84, engage the respective projections 68, 69 on one side thereof while the heads of bolts 86, 87 engage said projections on the opposite side. It will thus be seen that movement of the friction member 60 under the influence of the springs upon release of the gear is positively limited by the heads of the bolts aforesaid so that said friction member cannot be moved by either set of springs beyond its central position. The two sets of bolts 83, 84 and 86, 87 aforesaid thus provide means for positively centering the friction member upon release regardless of variations in the action of the springs. 50

It will be seen that when the gear of Figures 11-13 is interposed between the coupler butt and yoke of Figures 1 and 2, in the same manner as the gear shown in those views, the movement of the coupler in draft acts through the yoke to bring into action simply the wedge 64 and associated friction mechanism at the rear of the member 60, said member 60 being prevented from moving forwardly by virtue of the engagement of the key 19 with the front edges of the slots 21, 21. When the coupler moves in buff, the yoke 6 and rear stop 13 prevent rearward movement of the wedge 64 and the coupler butt acts upon the wedge 63 not only to move said wedge and associated shoes with respect to the friction member 60 but also to move said friction member with respect to the shoes engaged by the wedge 64, 75

such movement of said friction member being permitted by the slots 24, 26 aforesaid. Thus, the shock absorbing capacity of the gear of Figures 11-13, like that of Figures 3-10, is greater for buff than for draft movements, there being greater relative travel of the friction surfaces in buff than in draft.

The terms and expressions which I have employed are used as terms of description and not of limitation, and I have no intention, in the use of such terms and expressions, of excluding any mechanical equivalents of the features shown and described or portions thereof, but recognize that various structural modifications are possible within the scope of the invention claimed.

I claim:

1. In a railway draft gear, a case having a web extending across the interior thereof, shock absorbing means including a wedge cooperating with said case, a retaining bolt engaging said wedge, said web having a boss slotted for reception of the body of said bolt and said web having an opening for receiving the head of the bolt during assembly of the parts, said boss also having a recessed interior for reception of the head of the bolt when the parts are in normal assembled position, and a washer seated on said boss and engaging said bolt and also having an extension projecting into the slot in said boss.
2. In a railway draft gear, a case having a web extending across the interior thereof, shock absorbing means including a wedge and a spring engaging said wedge, a retaining bolt engaging said wedge, said web having a boss engaged by said bolt, a slot in said boss for receiving the bolt and a washer mounted on said boss and engaging said bolt, said washer being also engaged by said spring.
3. In a railway draft gear, a case, friction elements in opposite walls of said case, friction shoes

engaging said elements on opposite sides thereof, projections in said case forming abutments for said elements, a wedge engaging said shoes, a spring disposed centrally of said case and engaging said wedge, said abutments having curved faces for accommodating said spring, pairs of springs on opposite sides of the first mentioned spring and acting upon the respective shoes, and extensions on opposite sides of each of said abutments and merging with said case, said extensions having faces curved for accommodating the springs of said pairs.

4. In a railway draft gear, a case having a web extending thereacross, shock absorbing mechanism comprising a wedge and a spring engaging the latter, a boss on said web having a recessed interior and a slotted portion, a retaining bolt engaging said web and having a head seated in the recess in said boss, and a washer mounted on said boss and having a projection providing a seat for the bolt, said washer also having an extension engaging the slot in said boss and having on its opposite face a projection for centering said spring, and said web having an opening for permitting insertion or withdrawal of the head of said bolt.

5. In a railway draft gear, a case having a web extending across the interior thereof, shock absorbing means including a wedge cooperating with said case, a retaining bolt engaging said wedge, said web having a plurality of slots therein, one of said slots being adapted for reception of an end of said bolt during assembly of the parts, and a key passing through another of said slots adapted to limit movement of said gear, said key being positioned behind the head of said retaining bolt to limit rearward movement thereof during compression of the gear.

ERNEST H. SCHMIDT. 40
